(57) **CLAIM**

The ornamental design for a modulator, as shown and described.

DESCRIPTION

FIG. 1 is a perspective view of a modulator showing my design.

FIG. 2 is a top view of the modulator of FIG. 1.

FIG. 3 is a bottom view of the modulator of FIG. 1.

FIG. 4 is a right-side view of the modulator of FIG. 1, the left-side view being a mirror image thereof.

FIG. 5 is a rear view of the modulator of FIG. 1.

FIG. 6 is a front view of the modulator of FIG. 1.

FIG. 7 is a perspective view of an alternative embodiment of the modulator.

FIG. 8 is a top view of the modulator of FIG. 7.

FIG. 9 is a bottom view of the modulator of FIG. 7.

FIG. 10 is a right-side view of the modulator of FIG. 7.

FIG. 11 is a left-side view of the modulator of FIG. 7.

FIG. 12 is a rear view of the modulator of FIG. 7.

FIG. 13 is a front view of the modulator of FIG. 7.

FIG. 14 is a perspective view of another alternative embodiment of the modulator.

FIG. 15 is a top view of the modulator of FIG. 14.

FIG. 16 is a bottom view of the modulator of FIG. 14.

FIG. 17 is a right-side view of the modulator of FIG. 14; and, FIG. 18 is a left-side view of the modulator of FIG. 14.

The broken lines shown in the drawings form no part of the claimed design.
